ADJUSTABLE STOP

Walter K. Taylor, Jersey City, N. J., assignor to
American Houses, Inc., New York, N. Y., a cor-
poration of Delaware

Application February 26, 1942, Serial No. 432,475

2 Claims. (Cl. 143—174)

This invention relates to a new and improved adjustable stop of the character described for use primarily in connection with the prefabrication of structural building units.

An object of the invention is to provide a stop of the character described which is of rugged and sturdy construction, which may be readily and cheaply manufactured and which is adapted for use in connection with a suitable abutment member to provide a fixed, rigid, sturdy structure to position structural elements which are to be sawn to predetermined lengths.

Other objects of the invention are to provide such a stop which is adjustable in connection with said abutment member; to provide such a stop which comprises means providing two metallic gripping surfaces adapted to engage said abutment element, at least one of said surfaces being formed of a relatively soft metal having a high coefficient of friction with respect to said abutment element.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which:

Figure 1 is a plan view of a device embodying one form of the invention in engagement with a suitable abutment element, portions of the device being shown in dotted lines for clearness;

Fig. 2 is a view in section of the device, the abutment element and a portion of a supporting table, along the line 2—2 in Fig. 1; and

Fig. 3 is a view in section of a modified form of stop showing the plug-equipped face of the slot-providing means therein.

There has been a demand, particularly in connection with the manufacture of prefabricated housing units, for a rugged, sturdy, easily adjusted stop which may be employed with a suitable abutment element to provide an angular support against which structural elements such as studs, joists, rafters, doors, floor boards and the like may be positioned before being sawn to predetermined lengths. It will be apparent that where the structural elements are particularly heavy, the stop and abutment element are sub-

jected to a severe battering. Where the stop is adjustable along the abutment element, and this condition is preferred, it has been found that frequently the stop slips and fails to hold against the severe treatment it must receive. Accordingly it has been found for example that where many studs are to be cut to predetermined lengths, slippage of the stop along the abutment element may result in a difference in the length of the first cut stud and those cut at a considerably later period, for as the stop slips on the abutment, the stud length increases.

This invention contemplates the provision of a rugged, sturdy stop which may be readily adjusted along a suitable abutment element and which, when clamped in position upon the abutment element, remains in that position despite the hammering and battering to which such a stop must be subjected.

One embodiment of the invention is shown in the drawing wherein 10 represents any suitable supporting table upon which there may be bolted or otherwise affixed an abutment element 12 which, as shown in the drawing, may be in the form of an angle iron, the upright portion 14 of the angle iron serving as an abutment against which structural elements may be positioned.

The adjustable stop may comprise preferably two relatively heavy members 16 and 18 affixed in spaced and substantially parallel relation to a plate 20, for example by means of the bolts 22.

As shown particularly in Fig. 2, this construction provides a heavy, narrow, inverted, U-shaped structure, the space between the elements 16 and 18 providing a recess for the reception of the upright portion 14 of the abutment member 12 and the plate 20 resting upon the upper edge of the portion 14 of the abutment member 12, so that the stop straddles the abutment member loosely. The inner faces of the elements 16, 18 are preferably substantially parallel with the sides of the upright portion 14 of the abutment member 12. A recess 24 is provided in the inner face of either element 16 or 18. As shown in the drawing, this recess is provided in element 18, the element which lies adjacent to the abutment face of the member 14, and this is a preferred condition for ease in manipulating and adjusting the stop.

The elements 16, 18 and 20 are preferably of hard metal, for example iron or steel. An adjustable plug of a softer metal, for example brass, is positioned within the recess 24 in the element 18 and is slidably mounted therein so that it may be moved toward and away from the abutment

surface of the portion 14 of the abutment member 12. This plug is shown in the drawing at 26 in position to engage firmly the surface of the element 12. A threaded member 28 in the nature of a large set screw is provided, extending through the element 18 and threaded therein and bearing against the inner face of the plug member 26. Adjustment of this set screw 28 causes the plug element 26 either to firmly engage the upright portion 14 of the abutment element 12 or to ride loosely in the recess 24.

When the set screw 28 is turned inwardly, forcing the soft metal plug 26 against the upright portion 14 of the element 12, clamping action takes place between the plug 26 and the element 16, one on either side of the upright portion 14. While the surface of contact between the soft metal element 26 and the upright portion 14 of the abutment element 12 is not so large as the surface of contact between the element 16 and the upright portion 14, the softer metal with its higher coefficient of friction firmly grips the surface of the upright portion 14 and slippage of the stop along the abutment element is prevented, even though the stop be subjected to severe hammering in operation. As shown in Fig. 1, a preferred construction is one in which the soft metal plug element 26 is positioned substantially centrally of the element 18. The plug may extend for a considerable distance along the surface of the abutment element 12 with which it is in engagement. The soft metal plug 26 may be of any desired size and shape. A plug of circular cross-section, such as is shown for example at 36 in Fig. 3, possesses certain desirable attributes. It is inexpensive to make and to fit in the associated elements and shows no tendency to bow under pressure, when in use.

The stop is provided with an extending arm or plate 30 which, as shown in Fig. 2, may be bolted to the under surface of the element 18. This arm or plate extends substantially at right angles to the abutment element 12 and forms therewith and with the end of element 18 and the plate 20 a right angle stop against which structural elements or other work may be positioned. The plate 30 is preferably of relatively heavy construction and preferably made of the same metal as that forming the elements 16, 18. As shown in Fig. 1, it may extend in width the full width of the stop, and this is preferred as it provides added stability to the device. The plate 30 should be of such length as to provide adequate support for the structural elements which it is intended are to be used with the device.

The operation of the device will be apparent from the description of the structure. It is to be understood that a saw or other cutting element is fixedly positioned with respect to the abutment element 12 and that the stop is then mounted upon the abutment, as shown for example in Fig. 2, at the desired distance from the saw. The set screw 28 is then adjusted to force the soft metal plug against the abutment element, thus clamping the stop in fixed position thereon. In this position, the stop with the abutment element provides a fixed rightangled abutment against which the material being sawn may be positioned and thus cut to fixed predetermined lengths. A stop such as has been shown and described will remain in

position, if properly adjusted, for long periods of time. It will not slip along the abutment element. It is resistant to hard wear and abusive usage and provides a tool of great utility especially where, as has already been pointed out, it is to be employed in connection with the prefabrication of a great many elements of standard lengths.

It will, of course, be understood that while the particular construction of the stop shown in the drawing and described in the specification is preferred, this construction may be altered or modified in many ways which will be apparent to those skilled in the art without departing from the scope of the invention.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all the generic and specific features of the invention herein described, and all statements of the scope of the invention which, as a matter of language, might be said to fall therebetween.

What is claimed is:

1. In combination, a work-receiving table, an abutment member affixed thereto and comprising an upright, substantially flat-surfaced, straight element formed of hard metal, and a stop adapted to be so affixed to said abutment as to withstand severe battering and comprising a hard metal element adapted to straddle said abutment, means providing a slot in said metal element for the reception of said abutment, means providing a recess in a wall of said slot, a plug of soft metal, having a higher coefficient of friction with respect to said abutment than does said slotted element, mounted slidably within said recess, means for forcing said plug into firm frictional engagement with said abutment, and sturdy shock-resistant means affixed to said hard metal stop and providing a work-engaging surface extending substantially parallel to the surface of said table, and perpendicularly from said abutment.

2. In combination, a work-receiving table, an abutment member affixed thereto and comprising an upright, substantially flat-surfaced, straight element formed of hard metal, and a stop adapted to be so affixed to said abutment as to withstand severe battering and comprising a hard metal element adapted to straddle said abutment, means providing a slot in said metal element for the reception of said abutment, means providing a recess in a wall of said slot, a plug of soft metal, having a higher coefficient of friction with respect to said abutment than does said slotted element, mounted slidably within said recess, said recess and said plug being circular in cross-section, means for forcing said plug into firm frictional engagement with said abutment, and sturdy shock-resistant means affixed to said hard metal stop and providing a work-engaging surface extending substantially parallel to the surface of said table, and perpendicularly from said abutment.

WALTER K. TAYLOR.
